CONSOLE FOR A BICYCLE

Donald A. Wolf, Dayton, Ohio, assignor to The Huffman
Manufacturing Company, Miamisburg, Ohio, a corporation of Ohio

Filed July 3, 1967, Ser. No. 7,688

Term of patent 14 years

(Cl. D90—1)

FIG-1

FIG-7

FIG. 1 is a perspective view of a console for a bicycle showing my new design;

FIG. 2 is a plan view thereof;

FIG. 3 is a side view thereof;

FIG. 4 is a bottom view thereof;

FIG. 5 is another side view thereof;

FIG. 6 is one end view thereof; and

FIG. 7 is the other end view thereof.

The bicycle and control lever, partially shown in broken lines in FIG. 1, are included for illustrative purposes only.

I claim:

The ornamental design for a console for a bicycle, substantially as shown and described.
